Garrison Wilkinson
Setters Patent

The Schedule referred to in these Letters Patent and making part of the same containing a description in the words of the said Garrison Wilkinson, himself, of his improvement in the addition of hub and spokes of carriage wheels.

A specification of a newly invented article, a hub of the article, hub and spokes for all kinds of wheel carriages, invented by Garrison Wilkinson of the Town of White Plains, County of Westchester and State of New York. First. The article, the hub, including the two arms that go into the hub, is in fine parts. The arm is driven through the hub and does not turn in the hub, but is, tight in the hub, and the wheel and arm turn together. The hub may be made of wood, brass, cast iron, or any metal. If of wood, the arm is made four square when it goes through the hub, and is, driven in from the sides of the hub and taper, and when it passes out of the hub, it extends far enough to make a slot and fit a nut on the outer end of the arm, so as to make the hub fast and tight to the arm.

If the hub is cast iron, brass, or composed of other metal (and it may be made of any and every metal,) then the hub is cast solid and then on the inside of the hub a hole is drilled from one to three inches for the arm, according to the size of the carriage, and the arm with a screw on the end is screwed tight into the hub, and to prevent it from unscrewing a brace of iron in the form of a plate of iron, or other metal is first made with a hole to admit the screw part of the arm to pass through so that when tightly screwed up the plate is tight against the hub on the outside face of the inside of the hub and the plate is to be screwed tight in that position by two or more screws fastening it to the hub. The hole is four square through the plate and so is the arm where it seats (screwing however to a wood)

In the wooden hub the spokes are to be driven in solid through to the arm and as near to the very shoulder or big end of the hub as possible, so in the cast iron hubs, wooden hub, holes for the spokes are to be drilled in the same place with a double tenon and spokes are to be driven tight as before. The hub of metal, brass or cast iron for common carriages to be three or four inches long. The seat of the wheel to be in usual way, only there are no boxes in the hub. Each arm is to be in length about one third the width of the carriage from the hub or bearing outward from the wheel. The arm is always of wrought iron or steel, and that part extending outward from the hub is fastened to the axletree by one double box in two parts, and one single box. The first or double box is close to the hub and the part of the arm turning in double boxes is turned inward with shoulders, so as to keep it's place the residue of the outward arm is also turned in two parts, and the single box is on the farther end of it confined solid in the axletree and a screw and nut are on the end of the arm near the single box, to keep it from drawing out of box, and the outer part of the other beyond the hub turns in the boxes when the carriage moves the wheel, and the part of the arm in the hub turning together. The axletree and the part of the arm beyond the hub are put together with nuts and screws. The other wheel and arm on the other end of the axletree are made and fitted in the same way, with braces of iron or cast steel top and bottom of axletree, fastened to standards of iron and axletree, put together as shown by drawing, herewith shown and delivered and hubs are named with tubes or globes of very metal to hold oil, or to receive oil to fill boxes being or standing on the top or sides of axletree, being four on each axletree and one to each box with a screw stopper to make them tight, in the wooden hub the spoke is to be put with a double round tenon. The axle tree may

107

be made of any length of cast iron or wood or wrought iron
and in three parts without swarers, and the aforesaid drawing
shows the section of the same with one arm attached and with
one off. The Braps cast iron or metal hats, are to be cast
with a rim projecting over the end of the axle tree as rings
usually do. The axle tree may be cast in parts of iron, brass
or steel, and then fitted according to the drawing

November 19th 1831.
